Specification for Design.

Patented Oct. 25, 1921.

Application filed May 7, 1921. Serial No. 467,585. Term of patent 7 years.

To all whom it may concern:

Be it known that I, ABEL COLE, a citizen of the United States, residing at Chicago, in the county of Cook and State of Illinois, have invented a new, original, and ornamental Design for a Tie-Holder and Similar Article, of which the following is a specification, reference being had to the accompanying drawing, forming a part hereof.

In the drawing, Figure 1 is a front elevation of a tie holder or similar article, showing my new design.

Fig. 2 is a plan view thereof and Fig. 3 an end view thereof.

I claim:

The ornamental design for a tie holder or similar article, as shown.

ABEL COLE.
